(57) CLAIM

The ornamental design for a head cover of golf club, as shown and described.

DESCRIPTION

FIG. 1 is a perspective view of a head cover of golf club showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a view illustrating a state in which a flap of the head cover of golf club is opened.

The dotted lines represent stitching.
